UNITED STATES PATENT OFFICE.

JOHN H. BREWER, OF LOUISVILLE, KENTUCKY.

FLAG-COVER.

1,228,092.

Specification of Letters Patent.

Patented May 29, 1917.

Application filed September 19, 1916. Serial No. 121,023.

To all whom it may concern:

Be it known that I, JOHN H. BREWER, a citizen of the United States, and resident of Louisville, in the county of Jefferson and 5 State of Kentucky, have invented certain new and useful Improvements in Flag-Covers, of which the following is a specification.

My invention provides a very simple and 10 effective cover for flags which is arranged so that it is always connected with some part of the flag or staff and is therefore always ready for use and not likely to be lost. In one position the cover incloses the 15 flag and provides a dust and water-proof case for it, and in another position the cover is rolled around the staff below the flag where it is out of the way and yet ready for promptly covering the flag again. The invention 20 also enables flags to be used for drilling implements in addition to their ordinary use as will be described later.

The characteristics and advantages of the invention will be further described so far as 25 may be necessary in connection with the detailed description of the accompanying drawing which shows certain exemplifying embodiments of the invention. It is to be understood, however, that the invention 30 may be embodied in other forms and I do not limit myself to details, except as claimed.

In the drawing:

Figure 1 is an elevation showing the flag 35 unrolled and the cover wrapped and tied about the pole.

Fig. 2 is a similar view showing the flag rolled and the cover wrapped and tied about the flag.

40 Fig. 3 is an enlarged detail showing one method of attaching the cover to the pole.

Fig. 4 is an elevation of a modification showing the cover spread out to exhibit one method of attaching the cover to the pole.

45 Fig. 5 is an enlarged detail of the attachment device of Fig. 4.

Figs. 3 and 4 show the cover 1 spread out and attached to the pole below the flag in two different ways. The cover is a substantially rectangular piece of fabric of any suitable kind to afford the necessary protec-

tion, such as plain or water-proofed canvas, or a composition rubber fabric or the like. At one corner, 2, the cover is attached to the pole 3 near the lower edge of the flag 4. 55 This attachment may be as shown in Fig. 3, by slitting the cover at 5 to form a tongue 6 and this tongue is lashed to the pole by a cord 7. When this method of attachment is used, when the flag is unfurled the cover is 60 placed in the position shown in Fig. 3 and rolled about the pole as shown in Fig. 1 and lashed by the lashing cords 8, and in this position the side 1^a of the cover will be outermost. When the flag is furled the cover 65 is unlashed and opened and then turned up so that the other side 1^b of the cover is outermost, and then the cover is rolled about the flag and again lashed as shown in Fig. 2, affording a complete protection to the flag 70 against dirt and moisture.

In this position of the cover the flag is tightly secured about the pole and the entire device then becomes substantially a wand which may be used as a substitute for a 75 gun or other weapon in drilling.

When it is desired to have the same side of the cover outward in either of its positions such an attachment as shown in Figs. 4 and 5 may be used, consisting of a stud or 80 button 9, secured to the shaft and passing through an eyelet or buttonhole 10 in the corner of the cover. In this case the cover may be swung around on the stud as a pivot and rolled in either position with the same 85 side outward.

Evidently, other methods of attachment may be employed and the shape and mode of fastening the cover, and other details may be varied considerably within the principles 90 of the invention as explained.

What I claim is:

1. The combination with a flag or banner and its staff, of a cover consisting of a sheet of fabric secured to the staff near one edge 95 of the flag, and adapted to be rolled about the flag when furled, or to be rolled about the staff below the flag when the flag is unfurled.

2. The combination with a flag and staff, 100 of a cover secured to the staff so that it may be rolled about the flag when furled or

about the staff below the flag and means for fastening the cover when rolled in either position.

3. The combination with a flag and its staff of a cover consisting of a piece of fabric secured to the staff near one of its corners at a place on the staff near the lower

edge of the flag, and fastening devices on the cover, the parts being constructed and arranged so that the cover may be rolled about the flag when furled or rolled about the staff below the flag and secured in either position. 10

JOHN H. BREWER.
